SAFETY CONTROL AND IGNITION APPARATUS FOR GASEOUS FUEL BURNERS

Charles K. Strobel, Pittsburgh, Pa., assignor to Robertshaw-Fulton Controls Company, a corporation of Delaware

Application August 26, 1946, Serial No. 693,063

10 Claims. (Cl. 158—117.1)

1 This invention relates to safety control and ignition apparatus for gaseous fuel burners and, more particularly, to an electrical ignition system for use with electrically operated safety controls or oven burners.

In the copending application of Strobel and Lakota, Serial No. 620,320, filed October 4, 1945, owned by the applicant's assignee, there is disclosed a flash-tube ignition system in which a thermoelectric safety device is operated by manipulation of the oven thermostat knob and by a thermal timing device during the so-called resetting operation. Thus, when the thermostat knob is turned to "On" position, gaseous fuel is supplied directly to a heater for the thermocouple of the thermoelectric safety device. Simultaneously, the thermoelectric safety valve is latched in a starting position where the flow of fuel to the main burner is prevented but flow of fuel to an auxiliary pilot and to the oven flash-tube ports is permitted. After a predetermined time, the auxiliary pilot flame causes the thermal timer to operate and automatically release the latch. This causes the fuel supply to the auxiliary pilot and oven flash-tube ports to be shut-off. If, at the expiration of this predetermined period, the thermocouple has been sufficiently heated by the flame at the thermocouple heater, then the flow of fuel to the main burner will be permitted. The safety feature of preventing the flow of main burner fuel during resetting and whenever the flame is extinguished during normal operation are thus present.

There exists a demand for a safety control and ignition system of the foregoing described type but, at the same time, there is also a demand for a system embodying electrical ignition instead of the flash-tube ignition described. An object of this invention, therefore, is to electrically ignite gaseous fuel burners having the safety control features described.

Another object of the invention is to utilize the principal features of the flash-tube system in the electrical ignition system so that conversion from one to the other is facilitated.

Another object of the invention is to utilize power from an outside source for starting purposes only and thereafter to place the safety control system under sole influence of the thermoelectric means.

Another object of the invention is to utilize the electrical ignition means during the starting period only and thereafter discontinue exposure thereof to the heat of any flame.

Other objects and advantages will become ap-

2 parent from the following description taken in connection with the accompanying drawings, wherein:

Fig. 1 is a perspective view of a safety control and ignition apparatus for an oven fuel burner embodying the invention;

Fig. 1a is a perspective view of a portion of the apparatus shown in Fig. 1 but in modified form;

Fig. 1b is a perspective view of a portion of the apparatus shown in Fig. 1, but further modified;

Fig. 2 is a longitudinal sectional view of the electromagnetic control device shown in Fig. 1;

Fig. 3 is an elevation of the resetting device for the control device shown in Fig. 2;

Fig. 4 is a front elevation of another portion of the resetting device; and

Fig. 5 is a plan view of the resetting device shown in Fig. 4.

Referring more particularly to Fig. 1 of the drawings, the safety control and ignition apparatus is shown in connection with a cooking range having the usual oven burner 10 and top pilot burner 12 located remotely from the oven burner 10. As is customary in equipment of this nature, the various burners receive fuel from the manifold 14 connected to a source of fuel supply. In this embodiment the top pilot burner 12 is connected by a pipe 16 to the manifold 14 and is of the constant burning type.

30 The main oven burner 10 is supplied with fuel from the manifold 14 by a main fuel pipe 18 and the fuel supply therein is under control of means comprising a main fuel cock 20 which may also embody the usual thermostatic control

35 device (not shown) adjustable together with the cock 20 by knob 21 and being responsive to temperature in the oven where the burner 10 is located. As such combined fuel cocks and thermostatic devices are well known further de-

40 scription is deemed unnecessary, it being understood that the thermostatic device is capable of controlling the flow of fuel in the pipe 18 independently of the fuel cock 20 when the latter has once been opened. The flow of fuel in the pipe 18 to the main burner 10 is thus subject to the throttling action of the thermostatic device where included.

45 The flow of fuel in the pipe 18 to the main burner 10 is also under the control of a thermomagnetic control device designated generally by the reference numeral 22. This thermomagnetic control device 22 is interposed in the main fuel pipe 18 in proximity of the top pilot burner 12 between the main fuel cock 20 and the oven burner 10. As shown more clearly in Fig. 2, the

control device 22 comprises a casing 24 having an inlet connection 26 extending through the side wall of the casing 24 adjacent one end and communicating with a main fuel chamber 28 extending axially of the casing 24. The main fuel chamber 28 is provided with a partition 30 having an opening 32 therethrough through which the fuel may flow from the inlet 26 to an outlet 34 formed in the wall of the casing 24 at the opposite end of the chamber 28. The inlet 26 and outlet 34 serve as connections for opposite ends of the fuel pipe 18 as will be apparent from Fig. 1 of the drawings.

The passage 32 is controlled by a safety valve 36 which is movable into and out of engagement with a valve seat 38 formed on the side of the partition 30 adjacent the inlet opening 26. The valve member 36 is secured to a valve stem 40 which extends to the opening 32 and has slideable engagement with the closure disc 42. The purpose of the closure disc 42 is to interrupt the flow of fuel to the passage 32 when the valve member 36 is moved out of engagement with the seat 38 during the resetting operation to be described hereinafter. To this end, a second valve seat 44 is formed on the partition 30 on the side opposite the valve seat 38 and is adapted to be engaged by the closure disc 42 during the resetting operation. A guide portion 43 is formed substantially concentric with the closure disc 42 for cooperation with the walls of the opening 32 and may be serrated to permit free passage of fuel thereby until the closure disc 42 is fully engaged with its seat 44.

The bottom of the chamber 28 is provided with an annular projection or housing 46 in which a stem portion 48 of the closure disc 42 is slidably mounted. A coil spring 50 is carried by the stem 48 and is operative between the housing 46 and a collar 52 formed on the stem 48. Thus, when a force is applied to the end of the stem 48 to move the closure disc 42 into engagement with its seat 44, the coil spring 50 will be compressed. When the force is removed, the bias of the spring 50 will serve to return the closure disc 42 to its open position relative to the seat 44.

A yieldable connection is provided between the closure disc 42 and the valve member 36 to permit relative movement therebetween as will be more apparent hereinafter. To this end, there is provided an override mechanism in association with the closure disc 42 and the valve stem 40 which may take the form of a coil spring 54 housed within an axial recess in the closure disc stem 48 and operative between the bottom of this recess and the end of the valve stem 40.

The end of the casing 24 adjacent the inlet 26 is provided with a closure cap 56 having a magnet housing 58 closely engaging the inner wall thereof. The closure cap 56 at its outer end supports a threaded terminal connection 60. The magnet housing 58 supports a horseshoe magnet 62 which is provided with the usual winding 64 having one end grounded on the closure cap 56 and the opposite end secured to the terminal connection 60. The electro-magnetic device is completed by the provision of an armature 66 carried by the valve stem 40 for cooperation with the pole faces of the magnet 62. It will be noted that the armature 66 is normally spaced from the magnet 62 a less distance than the closure disc 42 is spaced from its seat. Thus, after the armature 66 is in attracted position, the override spring 54 will permit further movement of closure disc 42 relative to the valve stem 40. When the valve mem-

ber 36 is fully disengaged from its seat 38, then the armature 66 is in attracted relation relative to the pole faces of the magnet 62. The valve member 36 is biased to its seat 38 and the armature 66 to its released position by the provision of a coil spring 68 operative between the valve member 36 and the bottom of the magnet housing 58.

The control device 22 also includes means to control the supply of fuel to a thermocouple heating burner 70 and an auxiliary pilot burner 72. As shown in Fig. 1, the thermocouple heating burner 70 is located in the oven compartment adjacent the main burner 10 while the auxiliary pilot burner 72 is located adjacent the top pilot burner 12. Both burners are supplied with fuel by a pipe 74 extending from the control device 22, the auxiliary pilot burner 72 being conveniently connected to pipe 74 by a branch pipe 76. The inlet for fuel to the pipe 74 is connected to the control device 22 and may take the form of a pipe 78 connected at the opposite end to the main fuel cock 20. The fuel in the pipe 78 is preferably under control of the main fuel cock 20 but is not controlled by the thermostatic device which may be included as previously described. Thus, when the main fuel cock 20 is open, the flow of fuel in the pipe 78 is not subject to the throttling action of the thermostatic device as is the fuel in the pipe 18.

As previously indicated, the thermomagnetic control device 22 is also adapted to control the flow of fuel to the thermocouple heating burner 70 and the auxiliary pilot burner 72. To this end, as shown more clearly in Fig. 2, the pipe 78 is connected to an inlet opening 80 extending through the wall of the casing 24 and communicating with an auxiliary fuel chamber 82 formed axially of the casing 24 and separated from the main fuel chamber 28 by the housing 46. In order to prevent leakage of fuel from one chamber to the other, the auxiliary fuel chamber 82 is provided with a diaphragm 84 extending thereacross adjacent the end of the closure disc stem 48 and maintained in position by means of a clamping ring 86 carried by the casing 24.

The bottom wall 88 of the chamber 82 is provided with a plurality of apertures 90 providing passage for fuel from the inlet 80 to an outlet 92 formed in the wall of the casing 24 on the opposite side of the bottom wall 88 and adapted for connection to the fuel pipe 74. Passage of fuel through the apertures 90 is controlled by an auxiliary valve member 94 which is movable into and out of engagement with the bottom wall 88 of the chamber 82 within which the valve member 94 is located. A valve stem 96 is secured to the valve member 94 and extends on either side thereof. One end of the valve stem 96 is located in the chamber 82 and terminates adjacent the diaphragm 84.

The auxiliary valve member 94 is biased into engagement with the wall 88 by a coil spring 97 carried on the opposite end of the stem 96 and which is operative between the wall 88 and a collar 98 carried on the valve stem 96. This opposite end of the valve stem 96 terminates beyond the collar 98 for operative engagement with a second diaphragm 100 which serves to prevent leakage of fuel from the casing 24 and is held in position by a second clamping ring 102 carried on the casing 24. A reset stem 104 extends adjacent the underside of the diaphragm 100 through the bottom wall of the casing 24 and is provided with a button 106 exterior of the casing 24 and

by means of which the reset stem 104 may be reciprocated.

The electromagnet comprising the winding 64 and horseshoe magnet 62 is adapted to be energized by current generated from the thermocouple 108 which is connected by suitable leads 110 to the terminal connection 60. The thermocouple 108 is located so that the hot junction thereof will be heated by the flame from the thermocouple heating burner 70. If desired, an ignition pilot burner 114 may be provided intermediate the thermocouple heating burner 70 and the main burner 10 and may receive fuel from a conduit 116 connected to the pipe 78. However, as shown in Fig. 1a the ignition pilot burner 114 may be dispensed with and the thermocouple 108 located to be heated by a flame from the thermocouple heating burner 70 and from the main burner 10. A further variation would be to dispense with the thermocouple heating burner 70 and locate the thermocouple 108 to be heated by the ignition pilot burner 114 only, as shown in Fig. 1b.

A flash-tube 118 is provided between the constant burning top pilot burner 12 and the auxiliary pilot burner 72. The arrangement is such that fuel from the pipe 76 flowing from the auxiliary pilot burner 72 will enter the flash-tube 118 and be ignited from the constant pilot burner 12. The flame so created will then be conducted back through the flash-tube 118 and will ignite the fuel flowing from the auxiliary pilot burner 72.

In this embodiment of the invention, the thermocouple heating burner 70 or, alternatively, the ignition pilot burner 114 of Fig. 1b is provided with electrical igniting means. This means takes the form of an igniter 115 which, as shown in Fig. 1, is located adjacent an igniter port 117 on the thermocouple heating burner 70. The opposite ends of the igniter 115 are connected by wires 119 and 121 respectively to the opposite terminals of the secondary of a transformer 123. The primary of the transformer 123 has its opposite terminals connected by wires 112 and 125 to the opposite poles of a double-break switch 127 having one end of a pivoted operating element 129 associated therewith. The opposite end of the operating element 129 is secured to the button 106 as shown more clearly in Fig. 2. The switch 127 is thus adapted to be opened and closed by operation of element 129 as will be apparent hereinafter and when closed will connect wires 112 and 125 to line wires 131 and 133 respectively. The line wires 131 and 133 are connected to a suitable source of electrical energy, such as 115 volts house current, and the transformer 123 will serve to step down this current to approximately 6 volts for consumption at the igniter 115.

It is apparent that energization of the igniter 115 when the switch 127 is closed will serve to ignite fuel flowing from the port 117 of the thermocouple heating burner 70. The flame so produced at the port 117 will serve to ignite fuel flowing from an adjacent port 137 also formed in the thermocouple heating burner 70. The flame from the adjacent port 137 serves to heat the thermocouple 108 which will energize the magnet 62 sufficiently to hold the armature 66 against the pole faces thereof. This thermoelectric current, however, is incapable of moving the armature 66 to this attracted position. Hence, resetting means are provided for placing the armature 66 in attracted position and will now be described in connection with the detailed views in

Figs. 3, 4 and 5, together with the more general showing of Fig. 1 of the drawings.

The control device 22 is provided with a bracket 124 extending toward the top pilot burner 12 and forming a support for the auxiliary pilot burner 72. The bracket 124 is provided with a channel-shaped portion 126 at the end opposite the control device 22 and projecting substantially midway across the bracket. The channel-shaped portion 126 provides spaced bearings for a pivot 128 upon which a latching member 130 is mounted. The latching member 130 is preferably made in two parts, one slidable on the other which carries the pivot 128, and biased apart by means of a coil spring 132 interposed therebetween. The slideable portion of the latching member 130 is provided with a slot 134 extending across one end thereof and offset from the center. Extending between the slot 134 and the reset button 106 is a timing device comprising a bimetal strip 136 which is retained in position on the reset button 106 by the provision of a transverse slot 138 disposed centrally thereof. Pivotal movement of the latching member 130 is restricted by its engagement with the channel-shaped portion 126 in a counter-clockwise direction and by its engagement with a set-screw 140 carried by the channel-shaped portion 126 in the opposite direction.

As shown more clearly in Fig. 3, although the resetting button 106 is unoperated, the bimetal strip 136 occupies a position at an angle to the axis of the control device 22. In this position the bimetal strip 136 is offset from the auxiliary pilot burner 72 which projects through the bracket 124 substantially midway between the control device 22 and the channel-shaped portion 126. Manually operable means for moving the bimetal strip 136 and latching member 130 into substantial alignment with the axis of the control device 22 are provided and it will be apparent that in such position the bimetal strip 136 will be subject to the heat of the flame from the auxiliary pilot burner 72. Moreover, in this position, the reset button 106 will be forced inwardly of the control device 22 to effect the resetting operation.

The manually operable means includes a lever 142 provided with an angular portion 144 on one arm thereof having an aperture 146 therethrough in which the slideable portion of the latching member 130 is received. The lever 142 is pivoted on a pin 148 projecting from the bracket 124 on one side of the channel-shaped portion 126. The other arm of the lever 142 is engaged by a flexible connection in the form of a cable or pull wire 150 which is mounted on the bracket 124 and is provided with a coil spring 152 operative between the bracket 124 and the lever 142 for biasing the latter in a counter-clockwise direction. As shown in Fig. 3, when the lever 142 is thus biased the bimetal strip 136 is held in its angular position out of the path of the flame from the auxiliary pilot burner 72.

The pull wire 150 extends toward the manifold 14 of the range and is connected by means now to be described with the main fuel cock 20 for operation by the knob 21. To this end, the fuel cock 20 is provided with a bracket 154 (Figs. 4 and 5) extending laterally therefrom and carrying a support 156 through which the pull wire 150 extends. The end of the wire 150 is connected to a lever 158 which is pivoted on a pin 160 carried by the bracket 154. Movement of the

lever 158 in one direction serves to exert a pull on the wire 150 against the bias of the spring 152 and thus permits operation of the latching element 130. Such movement of the lever 158 is effected by a slidable member 162 having a hooked end 164 adapted to operatively engage the lever 158. The slidable member 162 is movable in a path substantially normal to the axis of the fuel cock 20 by means of a toothed portion 166 on the slidable member 162 being adapted for engagement with a lug 168 carried by the knob 21. The slidable member 162 is supported on the bracket 154 and its movement relative thereto is limited by the provision of a slot 170 formed in the slidable member 162 for cooperation with a pin 172 carried by the bracket 154.

In order that the lug 168 on the knob 21 may pass beyond the toothed portion 166 on the slidable member 162, the latter is yieldably mounted on the bracket 154 to permit such movement. To this end, the slidable member 162 is maintained with the hooked end 164 thereon in engagement with the lever 158 by means of a spring wire 174 which may be mounted at one end on the pin 172 and having its opposite end hooked in a perforation 173 in slidable member 162. A stop in the form of an arm 175 is secured to the pin 160 and engages the bracket 154 to limit movement of the lever 158, as will be apparent hereinafter.

The pivoted operating element 129 for the switch 127 is secured to the button 106 so that reciprocation of the latter will cause the pivotal movement of the operating element 129. Thus, when the parts are in the position shown in Fig. 2 of the drawings, the switch 127 is in open position. However, when the button 106 is moved toward the control body 24 during the resetting operation, then the switch 127 will be closed due to pivotal movement of the operating element 129.

The operation of the safety control and ignition apparatus is as follows: It may be assumed that the constant burning pilot burner 12 is producing a flame and that the fuel cock 20 has been opened by means of rotation of the knob 21 in a clockwise direction as viewed in Fig. 4 to cause fuel to flow in the pipes 18 and 78 as far as the control device 22. Where an ignition pilot burner, such as the burner 114, is provided, this burner will receive fuel from pipes 78 and 116 at this time. This rotary operation of the knob 21 will cause the lug 168 to be moved in a clockwise direction into engagement with the toothed portion 166 on the slidable member 162 causing the pull wire 150 to be operated by means of the lever 158. The latching lever 142 will thus be moved against the bias of the spring 152 in a clockwise direction causing the latching element 130 to move the adjacent end of the bimetal strip 136 also in a clockwise direction until it is aligned with the axis of the control device 22 and in the path of the flame of the auxiliary pilot burner 72.

The set screw 140 is now engaged by the latching member 130 and it will be apparent that the reset button 106 is thus forced inwardly and is maintained in such position while the bimetal strip 136 is unheated due to the clockwise torque applied at the slot 134 to the bimetal strip 136 and the counter-clockwise torque applied at the set-screw 140 to the latching element 130. The lug 168 on knob 21 has moved under and released the toothed portion 166 during the opening movement of cock 20 due to the yieldable mounting of the slidable member 162. The reset spring 152 causes the slidable member 162 to be returned to its initial position as soon as the toothed portion 75

166 is released from the lug 168. The unheated bimetal strip 136 remains in the latched position independent of the force applied by the pull wire 150.

5 The inward movement of the reset button 106 causes the reset stem 104 to move the diaphragm 100 and cause movement of the auxiliary valve stem 96 axially against the bias of the coil spring 97 which causes movement of the auxiliary valve member 94 from its seat. Fuel is thus permitted to flow from the pipe 78, inlet 80 and chamber 82 through the apertures 90, outlet 92 and pipe 74 for supplying the thermocouple heating burner 70. Simultaneously, fuel flows through the branch pipe 76 to the auxiliary pilot burner 72.

10 During this resetting operation, the stem 48 of the closure disc 42 is engaged by the diaphragm 84 and is moved against the bias of the spring 50 into engagement with the seat 44. The valve

20 member 36 is simultaneously moved away from its seat 38, but fuel is prevented from flowing from the passage 32 to the outlet 34 to the main burner 10 due to the immediate seating of the closure disc 42. It may be noted that immediately prior to engagement of the closure disc 42 with its seat 44 that the armature 66 has been placed in contact with the pole faces of the horseshoe magnet 62. However, the closure disc 42 can thereafter be moved into engagement with the seat 44 due to the provision of the override spring 54 which is compressed during such movement due to the relative movement between the closure disc 42 and the valve stem 40.

25 The longitudinal movement of the reset button 35 106 causes the operating element 129 for the switch 127 to rotate on its pivot and to close the switch 127. The circuit of the transformer 123 is thus completed and the ignition coil 115 becomes energized. The thermocouple heating burner 70 is receiving fuel at this time as described and a flame is produced at the ports 117 and 137 due to operation of the igniter 115. Moreover, as the auxiliary burner 72 is receiving a supply of fuel, the flash-tube 118 causes ignition 40 of this burner from the constant burning pilot burner 12.

45 After a predetermined time delay during which the bimetal strip 136 becomes sufficiently heated by the flame from the auxiliary pilot burner 72, the strip warps and trips the latching element 130. This warping of the bimetal strip 136 causes the direction of the torque at the slot 134 to be changed from clockwise to counter-clockwise. Hence, the latching element 130 is rotated counter-clockwise and will move the bimetal strip 136 out of the flame of the auxiliary pilot burner 72 to its initial cold position and simultaneously relieve the force upon the reset button 106.

50 The system is now in its steady state operating condition. The retraction of the reset stem 104 has caused the auxiliary valve 94 to be moved under the bias of the spring 97 into engagement with its seat to prevent flow of fuel from the inlet 80 through the apertures 90 to the outlet 92 so that the flow of fuel through the pipe 74 to the thermocouple heating burner 70 and auxiliary pilot burner 72 is cut-off. However, the time for heating the bimetal strip 136 sufficiently to cause it to warp is made long enough so that the thermocouple 108 can become sufficiently heated by the flame from the thermocouple heating burner 70 (and the ignition pilot burner 114 where used) to generate current for energizing the winding 64 of magnet 62 before the auxiliary valve 94 is moved to closed position.

Such energization of the magnet 62 causes the armature 66 to be held in attracted position against the pole faces of the magnet 62 and the valve member 36 remains open. The closure disc 42 now becomes disengaged from the seat 44 under the bias of the coil spring 50. Flow of fuel from the inlet 26, passage 32 and outlet 34 to the main burner 10 is now permitted. This burner is ignited by the flame at the ignition pilot burner 114 or, in the embodiment disclosed in Fig. 1^a, by the flame at the thermocouple heating burner 70. The ignition coil 115 becomes deenergized upon retraction of the reset stem 104 due to the operating element 129 being rotated on its pivot by movement of the reset button 106 to open the switch 127.

It may be noted that in the embodiment of Fig. 1^a, where the ignition pilot burner 114 is dispensed with, it becomes necessary for the thermocouple heating burner 70 to be positioned to ignite the main burner 10. As the flow of fuel to this burner 10 is cut-off by closure of the auxiliary valve 94 when the resetting operation is completed and the closure disc 42 has only at that time left its seat 44, it is also necessary that the unconsumed fuel remaining in pipe 74 after the auxiliary valve 94 closes be relied upon to continue the flame at this burner 70 until the main burner 10 is ignited thereby. Moreover, after the thermocouple heating burner 70 ceases it will be necessary for the thermocouple 108 to be heated by the flame from the main burner 10. An advantage of the arrangement is that a 100-per-cent shut-off of fuel is obtained upon operation of the safety control.

Where, as in the embodiment of Figs. 1 and 1^b, the ignition pilot burner 114 is employed, it is unnecessary to locate the thermocouple 108 to be heated by the flame of the main burner 10 or to rely upon residual fuel in pipe 74 to ignite the main burner 10. In this arrangement, however, a 100-per-cent shut-off is not possible due to the pipe 116 being connected to pipe 78 ahead of the control device 22.

It will be observed, moreover, that in the embodiments of Figs. 1 and 1^a the ignition coil 115 is exposed to a flame only during the starting period. Thereafter, the fuel supply through the igniter port 117 is cut-off. This feature should prolong the life of the ignition coil 115 as will be apparent. However, the system can be arranged as disclosed in Fig. 1^b by dispensing with the thermocouple heating burner 70 and locating the igniter 115 near the ignition pilot burner 114. Thus, the flame from this ignition pilot burner 114 could be relied upon to heat the thermocouple 108 and also to ignite the fuel flowing from the main burner 10. In this embodiment, the pipe 74 would be plugged at its junction with the pipe 76 so that fuel would flow from the outlet 92 to the auxiliary pilot burner 72 only. The igniter in the arrangement of Fig. 1^b would, of course, be exposed continuously to the flame from the ignition pilot burner 114 during the starting and running periods.

If at any time during the operation of the apparatus the thermocouple 108 ceases to be heated by the flame from the ignition pilot burner 114, or the main burner 10 where the ignition pilot burner 114 is dispensed with, then the armature 66 will be released from the pole faces of the magnet 62 causing the valve member 36 to become engaged with its seat 38 and prevent flow of fuel to the main burner 10. The knob 21 may be operated in a counter-clockwise direction to its origi-

nal "Off" position upon termination of operation of the oven burner 10. During this return movement of the knob 21, the lug 168 will again pass under the toothed portion 166 but in reverse direction due to the yieldable mounting of the slideable member 162 on the bracket 154.

Electric ignition systems have in the past been objectionable where a thermal timer has been manually set. This is due to the fact that such devices will not recycle in case of power failure. In this invention it is not necessary for the system to recycle in such a case since it is controlled by the power generated by a thermocouple. The external power supply failure will thus not affect the steady state operation. It is apparent, moreover, that the same basic equipment may be used for either a flash-tube ignition system as disclosed in the aforesaid copending application or for the electric ignition system disclosed herein. In both cases an automatic means of resetting the thermoelectric safety device has been provided and is operable by merely manipulating the usual knob of a main fuel cock from "Off" to "On" position or to a desired temperature setting where a combined thermostat and main fuel cock is provided. It will be apparent that many changes can be made in the arrangement and combination of parts and in the details of construction shown and described within the scope of the appended claims.

I claim:

1. A safety control and ignition apparatus for fuel burners having main and auxiliary burners, comprising control means operable between positions and biased to one of said positions for controlling the flow of fuel to the main burner, electromagnetic means operatively associated with said control means and adapted when energized for holding the same in another said position; an electric igniter located in lighting proximity to the main burner, thermoelectric means responsive to a flame at the main burner for energizing said electromagnetic means sufficiently to hold the same in said other position but being incapable of actuating the same to said other position, reset means operable for resetting said electromagnetic means for holding said control means in said other position and energizing said igniter, said reset means including a device responsive to a flame at the auxiliary burner for rendering said reset means inoperative after a predetermined period of resetting operation during which said thermoelectric means has time to become heated.

2. A safety control and ignition apparatus for fuel burners having main, auxiliary and pilot burners and a source of electric energy, comprising control means operable between positions and being biased to one of said positions for controlling the flow of fuel to at least the main burner, electromagnetic means operatively associated with said control means and adapted when energized for holding the same in another said position, an electric igniter located in proximity of the pilot burner and connected to be energized from the source for lighting the pilot burner to produce a flame at the main burner, thermoelectric means responsive to the heat of a flame at the pilot burner for energizing said electromagnetic means sufficiently to hold the same in said other position but being incapable of actuating the same to said other position, and reset means operable for resetting said electromagnetic means for holding said control means in said other position and energizing said igniter, said reset

means including means effective upon operation of said reset means for maintaining the same in operative position and a device responsive to a flame at the auxiliary burner for rendering said maintaining means inoperative after a predetermined period of resetting operation during which said thermoelectric means has time to become heated.

3. A safety control and ignition apparatus for fuel burners having main, auxiliary and pilot burners, comprising a valve member movable between open and closed positions for controlling the flow of fuel to the main burner and being biased to a closed position, electromagnetic means effective when deenergized for causing said valve member to close, a thermoelectric generator adapted to be heated by a flame at the main burner for energizing said electromagnetic means, an auxiliary valve member movable between open and closed positions for controlling the flow of fuel to the auxiliary and pilot burners, manually operable reset means for opening both said valve members, means operatively associated with said reset means for interrupting the flow of fuel to the main burner, an electric igniter located in proximity of the pilot burner for igniting the same to produce a flame at the main burner, and means operable for closing a circuit to said igniter upon operation of said manually operable means, said reset means including means effective upon operation of said reset means for maintaining the same in operative position and a device responsive to a flame at the auxiliary burner for rendering said reset means inoperative after a predetermined period of resetting operation during which said thermoelectric generator has time to become heated and causing said auxiliary valve member to close and said igniter circuit closing means to be opened.

4. A safety control and ignition apparatus for fuel burners having main, auxiliary and pilot burners, comprising a first valve member movable between open and closed positions for controlling the flow of fuel to the main burner and being biased to a closed position, electromagnetic means effective when deenergized for causing said first valve member to close, a thermoelectric generator adapted to be heated by a flame at the main burner for energizing said electromagnetic means, an auxiliary valve member movable between open and closed positions for controlling the flow of fuel to the auxiliary and pilot burners, means operable to an open position independently of said first valve member for interrupting the flow of fuel to the main burner, an electric igniter located in proximity of the pilot burner for igniting the same to produce a flame at the main burner, switching means operable for closing a circuit to said igniter, and manually operable reset means for opening said first and auxiliary valve members and causing operation of said flow interrupting means, said manually operable means including a connection to said switching means for operating the same for closing said circuit, a latching device effective upon operation of said reset means for maintaining the same in operative position and a thermal element movable into the path of a flame at the auxiliary burner, said element being responsive to said flame for moving out of the path thereof after said generator has had time to become heated and causing said auxiliary valve member to close and said switching means to open said circuit.

5. In a control and ignition system for fuel burning apparatus having a source of electric

energy, the combination of an electric igniter for the fuel adapted to be connected to be energized from the source, manually operable shut-off means for the fuel supply, control means biased to a position to prevent said fuel supply at least when said shut-off means is moved to an inoperative position, electromagnetic means operatively associated with said control means and adapted when energized for holding the same in another position to permit said fuel supply, thermoelectric means adapted to be responsive to the heat of the burning fuel at the apparatus for energizing said electromagnetic means but insufficiently to overcome said bias, reset means operatively associated with said shut-off means and being movable therewith to a position for overcoming said bias and resetting said electromagnetic means for holding said control means in said other position, and a normally open switch controlling energization of said igniter and being operatively associated with said reset means for operation to closed position during the resetting operation.

6. A system as set forth in claim 5 wherein said reset means includes a latching device effective upon operation of said shut-off means to said inoperative position for maintaining said reset means in said position thereof and said switch in said closed position, and timing means operatively associated with said latching device for tripping the same after a predetermined period of resetting operation and being rendered effective by movement of said reset means to said position.

7. In a control and ignition system for fuel burners having main and pilot burners and a source of electric energy, the combination of an electric igniter for the pilot burner connected to be energized from the source, manually operable shut-off means for the fuel supply to the main and pilot burners, control means biased to a position to prevent said fuel supply to at least the main burner when said shut-off means is moved to an inoperative position, electromagnetic means operatively associated with said control means and adapted when energized for holding the same in another position to permit said fuel supply, thermoelectric means responsive to the heat of a flame at the pilot burner for energizing said electromagnetic means but insufficiently to overcome said bias, reset means operatively associated with said shut-off means and being movable therewith to a position for overcoming said bias and resetting said electromagnetic means for holding said control means in said other position, and a normally open switch controlling energization of said igniter and being operatively associated with said reset means for operation to closed position during the resetting operation.

8. A system as set forth in claim 7 wherein said reset means includes a latching device effective upon operation of said shut-off means to said inoperative position for maintaining said reset means in said position thereof and said switch in said closed position, thermally responsive timing means operatively associated with said latching device for tripping the same after a predetermined period of resetting operation, and heating means for said timing means effective upon movement of said reset means to said position.

9. In a control and ignition system for fuel burners having main and pilot burners and a source of electric energy, the combination of an electric igniter for the pilot burner connected to be energized from the source, manually

tatable shut-off means for the fuel supply to the main and pilot burners, control means biased to a position to prevent said fuel supply to at least the main burner when said shut-off means is moved to an inoperative position, electromagnetic means operatively associated with said control means and adapted when energized for holding the same in another position to permit said fuel supply, thermoelectric means responsive to the heat of a flame at the pilot burner for energizing said electromagnetic means but insufficiently to overcome said bias, reset means including a reset stem movable axially into operative engagement with said control means for overcoming said bias and resetting said electromagnetic means for holding said control means in said other position, a normally open switch for controlling energization of said igniter, switch operating means carried by said reset stem for closing said switch upon said axial movement of said stem, and connecting means extending between said shut-off means and said stem for causing said axial movement upon manual rotation of said shut-off means to said inoperative position.

10. In a control and ignition system for apparatus having a constant burning pilot burner, a main burner and an ignition pilot burner and a source of electric energy, the combination of an electric igniter for the ignition pilot burner and connected to be energized from the source, manually rotatable shut-off means for the fuel supply to the main and ignition pilot burners, a control body located adjacent the constant burning pilot burner, a valve member reciprocable in said body and biased to a closed position, a fuel inlet connection to said body from said shut-off means, a fuel outlet connection from said body to the main burner and controlled by said valve member, electromagnetic means in said body for

holding said valve member open, thermoelectric means responsive to the heat of a flame at the ignition pilot burner for energizing said electromagnetic means, a reset stem projecting exteriorly of said body and operatively engageable with said valve member for opening the same in a resetting operation when moved inwardly of said body, a normally open switch controlling energization of said igniter, switch operating means carried by the projecting portion of said stem for closing said switch during said resetting operation, means carried by said stem for interrupting flow between said fuel inlet and outlet connections during the resetting operation, a latching device, connecting means between said shut-off means and said latching device for operating the latter to latching position, an auxiliary pilot burner adjacent said latching device, means for igniting said auxiliary pilot burner from said constant burning pilot burner, and a bimetal element operable between said reset stem and said latching device for movement into the path of a flame at said auxiliary pilot burner, said element being responsive to said flame for releasing said latching device after a predetermined period during which said thermoelectric means becomes heated.

CHARLES K. STROBEL.
